MUFFLER FOR INTERNAL COMBUSTION MOTORS

Eugene A. Mattie, Coolidge Road, Norwell, Mass.
Filed Jan. 6, 1961, Ser. No. 81,069
2 Claims. (Cl. 181—56)

This invention relates to a muffler for the exhaust from combustion motors, an object of the invention being to provide a structure which is relatively small in volume and effective in noise-suppression as compared with prior mufflers, but with no additional increase in the back-pressure resulting from its use. The muffler hereinafter described has been found to operate in a highly satisfactory manner. It can also be cast in two parts of identical form in which there are no small passages subject to being clogged by soot or dirt. Other advantageous features will be apparent from the following description thereof and from the drawings, of which

FIGURE 1 is a plan view of a muffler embodying the invention;

FIGURE 2 is a side elevation of the same;

FIGURE 3 is a cross-section, on a larger scale, on the line 3—3 of FIGURE 4, but of a complete muffler;

FIGURE 4 is a plan view, on a larger scale, of one of the two parts of the muffler shown in FIGURES 1 and 2;

FIGURE 5 shows the diagram which would be formed by inking the edges of the blades of one cylindrical unit of the muffler and rolling the unit once on a plain sheet of paper;

FIGURE 6 is a fragmentary perspective view of blade structure within one cylindrical unit of the muffler;

FIGURE 7 is a perspective view of the same in another angular position; and

FIGURE 8 is a fragmentary perspective view of the same in still another angular position.

The muffler hereinafter described consists of one or more tubular units 10 in each of which is located a baffle structure 12 of novel design. One or more such units may be employed, two being shown in parallel in FIGURES 1 to 4. The baffle structure for a single unit is illustrated in FIGURES 6, 7 and 8. This structure may be fitted into but removable from a tubular casing, or it may be formed in identical halves which may be assembled in a one-piece or two-piece tubular casing 16 or may be integrally cast with semi-cylindrical casing parts 16' as indicated in FIGURE 3. When two such semi-cylinders 16' are secured together they form a complete muffler. For convenience, the baffle structure will be described separately, as illustrated in FIGURES 6, 7 and 8.

The baffle comprises a central axial stem 20 which is preferably rectangular in cross-section, the width being twice the thickness. A series of diametral ribs 22, 23 are uniformly spaced along the stem 20 and extend radially in opposite directions therefrom. These ribs have the same cross-section as the stem 20 and they meet the stem in such a way that narrower edges of the ribs and stem define two parallel planes which are spaced apart a distance equal to the width of the stem. Each of these planes and a corresponding half of the cylindrical casing 10 define a semi-cylindrical space within which is a series of curved blades 24 each of which is cylindrically curved about an axis which is transverse with respect to the axis of the casing. Each blade 24 subtends an arc of about 90° so that one end 26 of each blade is nearly tangent to a plane parallel to the axis of the casing while the other end 28 of the blade is tangent to a transverse plane. Each blade 24 has preferably the same thickness as the stem 20 or ribs 22, 23, so that the end portion 28 merges laterally with one of the ribs 23, the narrow end 26 being secured to or integral with an end of the rib next to the

2

one with which the broad end 28 is merged. The outer edge 30 of each blade 24 fits against the inner surface of the tubular casing 10. Each blade has an arcuate free inner edge 32 which extends from one rib 22 to the next rib 23 and lies in the plane defined by the adjacent edges of the stem 20 and ribs. The blades in one half of the casing all curve in the same sense, the blades in the other half curving in the opposite sense, so that the appearance of the baffle 12 is the same when viewed from either end. Each rib 23 merges at one side edge with a blade 24 of one series and at the other side edge with a blade 24 of the other series. Likewise, the outer end portion of each rib 22 is joined by end portions 26 of a rib from both series. To reinforce this joint and fill in the small space between the narrower ends 26 of the blades and the inner surface of the casing, a transverse segment 36 is provided integral with each pair of blade ends 26 and the end of the rib 22 between them. The outer edges of the blades 24 and segments 36 form an irregular double helix which is developed on a plane in FIGURE 5 of the drawings. The edge of each segment 36 is inclined slightly from a transverse plane. From either end of the segment the edge 30 of a blade 24 curves sharply through an arc of about 90°, then flattens to an almost straight section which represents the outer edges of the wide end portions 28 of a pair of blades 24 which merge with the same rib 23.

The number of blades in each series in a tubular casing may be varied, but twelve such blades in each series has been found to be desirable, that number being shown in each series in FIGURE 4. The size and certain dimensions of a muffler will vary according to the size and number of cylinders of the motor with which the muffler is used. The following table gives preferred dimensions for mufflers used with small one-cylinder or two-cylinder motors such as are used on lawn mowers, or as outboard marine motors, for four-cylinder motors such as are used in many small automobiles, and for six-cylinder and eight-cylinder motors such as are used in larger automobiles.

N=number of motor cylinders
D=interior diameter of the tubular casing
d=pitch length, i.e., the axial distance between successive ribs
a=width of the stem or a rib
b=thickness of the stem or a rib
Measurements are given in inches.

<i>N</i>	1	2	4	6	8
<i>D</i>	1.125	1.375	1.75	2.125	2.5
<i>d</i>	0.25	0.5	1.0	1.5	2.0
<i>a</i>	0.141	0.174	0.218	0.266	0.313
<i>b</i>	0.073	0.087	0.109	0.133	0.156

The baffle structure shown in FIGURES 6, 7 and 8 has been described as a separate article. By making it in two parts such as would be formed by cutting the article by an axial plane bisecting the stem 20 and all the ribs 22, each half can be conveniently cast integrally with a semi-cylindrical half of the tubular casing.

Such a casting of half of a double unit is illustrated in FIGURE 4. Two semi-cylinders 16 with separate baffles therein or 16' with integral semi-baffles are joined by a common flange 40 along their mutually adjacent side edges, flanges 42, 44 being provided along the mutually remote side edges. These flanges have faces in a common plane so that two castings can be bolted together to form a complete muffler, bolt holes 46 being provided for that purpose. At each end of the semi-cylinders is an extension 50 in the form of a Y-trough with rims 52 flush with the flanges 40, 42, 44. When two castings are bolted together, the troughs join to form Y-passages to and from the tubular casings. The castings are identical in every detail, one of them being reversed end-for-end before being bolted to the other.

Within each semi-cylinder 16' and integrally cast therewith are elements similar to those hereinbefore described as elements of a baffle structure 12. A stem 20' extends along the axis of each semi-cylinder, this stem being intersected by a uniformly spaced series of diametral ribs 22', 23'. The stem ribs are flush with the flange 40, 42, 44 and the rims 52. The stem 20' and ribs 22', 23' being halves of corresponding stem 20 and ribs 22, 23, have square cross-sections. In each semi-cylinder 16' is a series of blades 24' which are shaped and arranged with respect to the stem 20' and ribs 22', 23', exactly like the arrangement of one of the series of blades 24 of the baffle structure shown in FIGURES 6, 7 and 8. Thus when two units such as the one shown in FIGURE 4 are properly joined as shown in FIGURE 3, a complete double muffler is formed, the interior arrangement of which is exactly like the baffle structure in FIGURES 6, 7 and 8. By this construction, only one form of casting need be stocked as both parts are identical and can be individually replaced in case of injury or defect.

The herein illustrated baffle structure causes exhaust gases, in traveling through the chamber, to follow a circuitous path which contains a series of loops caused by the curved baffles, said loops having an axis which is perpendicular to the longitudinal axis of the housing.

I claim:

1. A muffler for the exhaust from an internal combustion motor, comprising two halves of identical form secured together, each said half comprising a semi-cylindrical casing part, an axial stem in said casing part, a series of arcuately curved blades disposed in each half with an edge thereof abutting the inner surface of the semi-cylinder, each said blade having a broad end portion

disposed in a transverse plane which is perpendicular to the axis of the semi-cylinder, the other end of each blade being narrower and at a steep angle to a transverse plane.

2. A muffler for the exhaust of an internal combustion motor, comprising two halves of identical form secured together, each said half being a unitary structure comprising two semi-cylinders joined side-by-side by a common flange, a flange along the other side edge of each semi-cylinder in the same plane with said common flange, an extension at each end of said semi-cylinders forming a Y-trough branching to the semi-cylinders, each said semi-cylinder having therein an axial stem, uniformly spaced radial ribs projecting from said stem, said stem and ribs being flush with said flanges, and a series of arcuately curved blades in each said semi-cylinder, each said blade having an edge thereof integral with the inner surface of the semi-cylinder in which it is located, each said blade having a broad end portion disposed in a transverse plane which is perpendicular to the axis of the semi-cylinder, the other end of each blade being narrower and at a steep angle to a transverse plane, each said blade having a free edge portion substantially in a plane defined by the edges of said semi-cylinders.
